UNITED STATES PATENT OFFICE.

FRANK A. HARLOW, OF BROOKLYN, NEW YORK.

PRINTING-PRESS.

SPECIFICATION forming part of Letters Patent No. 244,053, dated July 12, 1881.

Application filed March 9, 1881. (No model.)

To all whom it may concern:

Be it known that I, FRANK A. HARLOW, a citizen of the United States, residing at Brooklyn, in the county of Kings and State of New York, have invented a certain new and useful Improvement in Printing-Presses; and I do hereby declare that the following is a full, clear, and exact description of the same, reference being had to the annexed drawings, making a part of this specification, and to the letters and figures of reference marked thereon.

Figure 1 of the drawings is a perspective view of a printing-press constructed in accordance with my invention. Fig. 2 is a side elevation of the same with the platen against the face of the type; and Fig. 3 is a sectional elevation, showing the platen away from the bed.

The present invention has relation to that class of printing-presses known as "job-presses," and more particularly to those operating the platen by means of the well-known toggle-joint principle.

The invention consists in the particular construction of the mechanism for operating the platen and roller-frame, as illustrated in the drawings and hereinafter described.

In the accompanying drawings, A represents the frame, of any suitable form and construction, to which the several operating parts of the press are connected.

The platen B is connected by screws *a* or other suitable means to a frame, C, said frame being pivoted to the upper ends of perpendicular arms *b*, said arms at their lower ends being pivoted to the inner sides of the frame A. The frame C, which carries the platen B, is pivoted to a toggle-arm, *c*, which, in turn, is pivoted to a yoke, *d*, said arm and yoke forming together a toggle-joint connection between the frames A and C.

To the sides and lower extremity of the frame C are pivoted the ends of arms D, the opposite ends thereof being slotted to receive pins *e*, projecting from the sides of the frame A, to guide and steady the arms in their movement.

To the yoke *d* is pivoted or otherwise suitably connected a link, *f*, which is pivoted to the end of the rocking arm *g*, formed with or

rigidly connected to a horizontal shaft, *h*, which has its bearings in the sides of the frame A. These rocking arms are three in number, all radiating from the shaft *h*, the arm *i* having connected to it a link, *k*, which is pivoted to an operating hand-lever, E, the forward end of said lever being loosely connected to one of the cross braces or rounds *l*, which holds the sides of the frame A together.

To the third one of the rocking arms (represented at *m*) is pivoted one end of a rod, F, the other end thereof being pivoted to the roller-frame G, said frame, in turn, being pivoted to the press-frame A.

It will now be seen that by raising the hand-lever E to the position as shown in Fig. 3 of the drawings the platen B is retired from the face of the type, which are held within the frame H in the ordinary manner, and at the same time the platen is elevated to a convenient feeding angle. During this operation the rollers I are brought down to their inking position, and the reverse motion of the hand-lever E forces the platen against the type and gives the impression required, at the same time bringing the rollers I over and upon the revolving disk K, which distributes the ink. The disk K is caused to revolve in the usual manner by a ratchet-wheel, *n*, upon the under-side of the disk, and the pawl *p*, pivoted to the arm *r*.

The slotted arms D, as will be noticed, operate as levers to throw up the lower side or edge of the platen B and frame C to the position shown in Figs. 1 and 3 of the drawings, thus bringing it in a convenient angle for feeding.

The toggle-joint connection between the platen-frame C and press-frame A is operated by means of the link *f*, which is pivoted to one of the three rocking arms, having a common axis upon the shaft *h*. Thus it will be apparent that the vibration of the arm *g* will, through its link-connection above described, operate the toggle-joint. This arm *g* is given its vibratory motion by a hand-lever, E, which is connected to the arm *i* by link *k*.

The inking-rollers I are given their motion by the rod F, connected to the roller-frame G

and to the arm *m*, said rollers passing alternately over the inking-disk *K* and the face of the type.

Although I have shown a hand-lever for operating the press, treadle or any other suitable power may be employed.

Having now fully described the construction and operation of my invention, what I claim as new, and desire to secure by Letters Patent, is—

In a printing-press, the platen *B*, in combination with the sliding arms *D*, arm *b*, yoke-toggle *c d*, rocking shaft *h*, having arms *g i m*, lever *E*, roller-frame *G*, and connecting-links *f k F*, substantially as and for the purpose specified.

F. A. HARLOW.
